EDWARD J. SMITH, OF CLEVELAND, OHIO, ASSIGNOR TO MARY E. SMITH, OF CLEVELAND, OHIO

LAMP SHADE AND SUPPORT THEREFOR

Application filed May 3, 1929. Serial No. 361,294.

My invention relates to lamp shades and supports therefor, and especially concerns a lamp shade carrying a light bulb therein, and a clamping device for mounting the shade upon an open music stand. It is my especial purpose to provide a music stand supporting a horizontal table or shelf together with a plate inclined somewhat to the vertical, but having an upper curved edge upon which an illuminating member may be readily detachably mounted.

It is understood that lighting attachments for music stands or desks are old in the art, but all of them, so far as I am aware, have the serious objection of either unduly shading parts of the support which should be illuminated, or are of such a nature, usually because of the design of the shade, that the light is too bright in many directions from its source, and thereby produces an undesirable glare annoying to the user, and as I have found, quite unnecessary. It is an object of my invention to concentrate the light from the shade employed upon the sheets that may be resting on the supporting plate, and confining the light rays thereon, as much as possible.

It is a further object of my invention to provide a light shade of general triangular outline as shown in plan, having downwardly-extending flanges upon the sides and peak of the triangle, but providing the base of the triangular support with clamping flanges which are thus far removed from the light source.

Another object of my invention is the provision of a flanged shade of triangular outline whose base is provided with means for mounting upon a curved plate, and whose light bulb extends normally into the uppermost peak of the triangle and opposite the supporting clamp.

It is a still further object of my invention to provide a shade triangular in outline having downwardly-extending border flanges on all sides except the base line, which latter is provided with clamping means for engaging the convex surface of a supporting rack plate, and providing a socket at the intersecting angle of the tri-

angular side, for receiving a light bulb, so that the lateral expansion of light rays downwardly from the bulb will be increased progressively as the illuminated area nears the supporting plate, and is narrowest at the point farthest from the plate. As the user of such a music stand is assumed to be positioned in front of the rack or supporting plate and facing the same, the desirable object is attained of restricting the rays from the bulb most at the point nearest the user.

With these and other objects of my invention which will be made evident as the description proceeds, I have explained the structure of my lamp shade and support in the accompanying specification, recited the same in the appended claims, and illustrated the same in the accompanying drawings, in which—

Figure 1 is a side elevation of my shade and stand;

Figure 2 is a front elevation of the same;

Figure 3 is a vertical section taken in the plane indicated by the line 3—3 of Fig. 2;

Figure 4 is an inverted plan of the lamp shade;

Figure 5 is a cross section taken in the vertical plane indicated by the line 5—5 of Fig. 3;

Figure 6 is a vertical section taken in the plane of the line 6—6 of Figs. 3 and 4;

Figures 7 and 9 are sectional details as shown on the lines 7—7 and 9—9 of Fig. 4, respectively, and

Figure 8 is a sectional detail as taken on the line 8—8 of Figs. 3 and 4.

In the drawings I have illustrated the music stand supported upon a vertical standard 10 having a horizontal plate or shelf 11 mounted on its upper end and a tubular holder 19 at one lateral edge of the shelf, but parallel with and integral with said standard. The connecting web 8 directly supports the shelf 11. My improved supporting rack 12 has a straight lower edge to which is attached the flange member 13, and an upward curved edge 14 in which a deep notch 15 is formed for a purpose to be explained later.

The rack is directly mounted upon an angular member 16 which is preferably integral

with the sleeve 17 secured to an elongated rod 18 itself tubular and designed to fit telescopedly in the holder 19, the latter having the usual set screw 20 for vertically adjusting the rack. My shade 21 is supported detachably upon the said edge 14 of the rack, and in a general plane substantially at right angles thereto. The shelf 11 will usually remain in a fixed position upon the web 8, and the standard 10 will be supported conventionally, as by a tripod 22. The web 8 has an adjustment shoulder 9.

The curved edge 14 of the plate or rack 12 is convex, and my shade 21 is triangular in outline, and having a curved rear edge remote from the forward light pocket, the said curved edge fitting over the convex edge 14 of the rack 12. The edge 23 of the shade, as shown especially in Fig. 5 of the drawings, is provided with a central but downwardly-extending supporting tongue 24 which is designed to rest in the said notch 15 of the edge 14 of the plate 12. The edge 23 is provided on its lower surface with parallel clamping flanges 25 which engage opposite surfaces of said rack edge 14 to serve as supporting flanges to hold the shade 21 in positive position upon the rack 12, though detachably.

To avoid too loose mounting of the shade, the tongue 24 will rest in the notch 15, as before explained. Short ears 26 are formed integral with one of the flanges 25 and are provided with suitable apertures for receiving attaching screws entering the upper edge 14 of the rack. The point of the shade farthest removed from the base 23 of the shade, serves as the vertex 27 of the triangular outline of the shade and provides a socket or chamber 28 to receive the light bulb 29 which is mounted upon an apertured plate 30 which is hinged upon lateral ears 31 which swing upon a horizontal pintle 32 to permit the bulb 29 to be lowered into the dotted line position shown in Fig. 3, but the said pintle being provided with a coil spring 33 designed to hold the bulb 29 in its full line position in the socket 28.

The said pintle 32 is carried by downwardly-extending ears 34 from an adjustable plate 35 detachably mounted upon the inner surface 36 of the shade 21 about centrally thereof, as shown in Figs. 3, 4 and 9. The lower or under surface of such plate 35 is provided with parallel and longitudinal grooves 37 guided upon parallel tracks 38 integral with the shade.

The supporting plate 35, together with the light bulb and its mounting mechanism, is secured adjustably on the inner surface of the plate by a conventional screw bolt 39 extending through an aperture 40 in the shade 21 and extending through the elongated slot 41 in the plate 35, and provided with a wing nut 42 beneath the movable plate. By this means the

light bulb 29 carried by the swinging plate 30 may be readily adjusted toward and from the socket 28. Between the ears 34 and the vertex 27 a notched partition 43 is provided integral with the main wall of the shade 21, as shown in Figs. 3, 4, and 6. This provides a positive position for the bulb resulting from seating the neck of the same in the notch 44.

The tongue 24 is apertured at 45 to receive the suitable insulated conductor therethrough, and may be itself insulated by a lining sleeve 46 as shown in Fig. 3. In the normal position of the light bulb 29, the mounting plate 30 assumes a vertical position, when the standard 10 is vertical, and the pressure of the spring 33 forces the plate upward and forwardly until it bears against the standard 47 integral with the plate 35. In swinging upon its pintle 32 therefore, the bulb 29 may move downwardly and rearwardly, but cannot rise upwardly far enough to strike the material of the shade.

As above described, my improved construction provides a music rack 12 adjustable vertically relative to the shelf 11 which is well adapted for receiving various articles such as music sheets and even parts of instruments, and both the shelf and rack are illuminated from the same source without unnecessarily lighting space outside the general boundaries of these areas. The shade 21 is readily detachable from the convex edge of the rack 12, and the plate 35 carrying the bulb 29 is adjustable longitudinally within the shade. This together with the convenience of swinging the bulb upon its hinge, forms a construction that will be appreciated.

Rearwardly from the light units will extend the usual conductor 48, passing through the sleeve 46 and thence downwardly through the parts 17 and 18, and therefrom to a suitable electrical connection. Considering the director or other user of the device as standing in a position to face the rack 12, it will be seen that the flanged vertex 27 wholly protects his eyes from the glare of the rays leaving the bulb 29, though the sheets resting upon the rack 12 will be well illuminated. It is of especial importance that the vertex 27 of the shade is nearest the user, and that, due to the triangular outline of the shade, the area illuminated from this single bulb expands as the rack 12 is approached. The triangular form of the shade 21 therefore, has the valuable quality of illuminating a large field from a single bulb, at a point closely adjacent the rack supporting the sheets to be illuminated, and of intensifying the illuminating rays at points illuminated from the vertex of the shade.

Especial advantages are claimed for this improvement in that it affords a maximum of illumination from a single light bulb and thereby provides better light for musicians by a minimum electric current. The arrange-

ment of parts affords the greatest convenience in adjustment and in shifting to different parts of the room, as well as in lighting the shelf and rack from a single bulb.

5 Various changes may be made in the structure of the support as well as in the shade, and it is to be understood that some features may be modified without departing from the spirit of the invention or the scope of the appended claims.

10 Having thus fully described my invention what I claim as new and desire to secure by Letters Patent of the United States is:—

15 1. A music stand having a rack at the top thereof, a lamp shade having a downwardly extending flange in a vertical plane for mounting upon the upper edge of the rack, a lamp pivotally mounted on a horizontal pivot within said shade, and a supporting shelf beneath the shade and adjacent the lower edge of the rack, the said lamp being normally spring-pressed upwardly within and against the under surface of the shade but permitting swinging downward upon said pivot, the 20 said shade having a downwardly extending border flange to restrict the illuminated field substantially to the surface of said rack and the supporting shelf, and the said rack being vertically adjustable toward and from the 25 said shelf to vary the intensity of light directed upon the latter without varying the degree of illumination of the rack.

30 2. A music stand having a rack at the top thereof, a lamp shade of triangular outline having a downwardly extending flange in a vertical plane, for mounting upon the upper edge of said rack, a lamp pivotally mounted within said shade and normally spring-pressed upwardly within the shade at the 35 vertex of the triangle, and a supporting plate beneath the said shade, the said vertex having border flanges to restrict the illuminated field substantially to the surface of said rack, and the said plate.

40 45 3. A music stand having a rack at the top thereof provided with a convex upper edge, a lamp shade of triangular outline having a downwardly extending flange curved in a vertical plane, for mounting upon the said upper edge, the said flange forming the base of the triangle, a lamp pivotally mounted beneath said shade and normally spring-pressed against the shade at the vertex of the triangle, and a shelf mounted beneath the 50 said shade, and the sides of the triangle adjacent said vertex having border flanges diverging from the vertex toward said base, thereby restricting the illuminating rays from the lamp substantially to the surface of said rack and shelf.

55 60 65 4. A music stand having a rack at the top thereof, a lamp shade of triangular outline detachably mounted at the base of said triangle upon the upper edge of said rack, and having the vertex extended forward from

said rack, and a lamp pivotally mounted within said vertex, whereby the illuminating rays from the lamp will be directed downward upon both the rack and other portions of the stand, but will not be directed upwardly or laterally from said vertex. 70

5 75 80 85 5. A music stand having a rack at the top thereof, a lamp shade of triangular outline detachably mounted at the base of said triangle upon the upper edge of said rack, and having the vertex extended forward from said rack, the said vertex having border flanges gradually receding upwardly toward the roof of the shade and forming a light socket in the latter, and a lamp pivotally mounted within said socket, whereby the illuminating rays from the lamp will be directed downward upon both the rack and other portions of the stand, but will not be directed upwardly or laterally from said vertex. 85

90 95 100 105 6. A music stand having a rack at the top thereof, a lamp shade of triangular outline detachably mounted at the base of said triangle upon the upper edge of said rack, and having the vertex extended forward from said rack, the said vertex having border flanges gradually receding upwardly toward the roof of the shade and a notched partition connecting said border flanges and thereby forming a light pocket at said vertex, and a lamp pivotally mounted within said pocket, whereby the rays from the lamp will be directed downward upon the rack and other portions of the stand, but will not be directed upwardly or laterally from said vertex. 100

110 115 120 125 7. A music stand having a rack at the top thereof, a lamp shade of triangular outline detachably mounted at the base of said triangle upon the upper edge of said rack, and having the vertex extended forward from said rack and a flat plate adjustably mounted on the under surface of said shade for adjustment toward and from said vertex, and a lamp pivotally mounted within said vertex upon said plate for swinging in a vertical plane, whereby when the lamp is in its uppermost position, the rays therefrom will be directed downward upon the rack and other portions of the stand. 115

120 125 130 8. A music stand having a rack at the top thereof, a lamp shade of triangular outline detachably mounted at the base of said triangle upon the upper edge of said rack, and having the vertex extended forward from said rack and a flat plate adjustably mounted on the under surface of said shade for adjustment toward and from said vertex, a lamp pivotally mounted on the under surface of said shade and upon said plate for swinging in a vertical plane, and a shelf mounted adjacent the rack and beneath the shade, the said rack being vertically adjustable toward and from the said shelf to vary the intensity of light directed upon the lat-

ter without varying the degree of illumination of the rack, and the sides of the triangle adjacent said vertex having border flanges diverting toward the said base, thereby restricting the rays from the lamp substantially to the surface of said rack and shelf.

In witness whereof, I have hereunto set my hand this 4th day of May, A. D. 1929.

10**EDWARD J. SMITH.****15****20****25****30****35****40****45****50****55****60**
